(57) **CLAIM**

We claim the ornamental design for a wheel rim, as shown and described.

DESCRIPTION

FIG. 1 is a front perspective view of a wheel rim.
FIG. 2 is a rear perspective view of the wheel rim.
FIG. 3 is a front elevation view of the wheel rim.
FIG. 4 is a left side elevation view of the wheel rim.
FIG. 5 is a rear elevation view of the wheel rim.
FIG. 6 is a top plan view of the wheel rim; and,
FIG. 7 is a bottom plan view of the wheel rim.
The broken line showing is for the purpose of illustrating portions of the wheel rim and forms no part of the claimed design.

1 Claim, 7 Drawing Sheets
